United States Patent Office

Des. 196,417
Patented Sept. 24, 1963

196,417

FAUCET

Arthur M. Lander, 833 S. Cumberland Ave.,
Park Ridge, Ill.

Filed Oct. 30, 1962, Ser. No. 72,312

Term of patent 14 years

(Cl. D91—3)

FIG. 1 is a perspective view of a faucet showing my new design;

FIG. 2 is a front elevational view thereof;

FIG. 3 is a top plan view; and

FIG. 4 is a side elevational view.

I claim:

The ornamental design for a faucet, as shown.
